CLAIM

The ornamental design for a trash bag funnel, as shown and described.

DESCRIPTION

FIG. 1 is a front perspective view of a trash bag funnel showing my new design;

FIG. 2 is a right side elevational view thereof, the left side view being a mirror image of that shown;

FIG. 3 is a top plan view thereof.

FIG. 4 is a rear elevational view thereof.

FIG. 5 is a bottom plan view thereof.

FIG. 6 is a right side and front perspective view thereof, the broken lines are for illustrative purposes only.

FIG. 1

FIG. 2

FIG. 3

FIG. 4

FIG. 5

FIG. 6
